UNITED STATES PATENT OFFICE

HARRY MEACHEM, OF TEANECK, NEW JERSEY, ASSIGNOR TO TODD DRY DOCK, ENGINEERING & REPAIR CORPORATION, OF BROOKLYN, NEW YORK

BLOWER

Application filed September 25, 1930, Serial No. 484,358. Renewed June 29, 1932.

This invention relates to rotary blowers for use in supplying air or other fluid under pressure in a whirling stream, and my improvements are directed particularly to means in a blower that effect a conversion of the centrifugally directed fluid flow into a whirling column without loss of velocity such as is now involved in changing the direction of the fluid flow delivered by the blowers in use.

With this and other objects in view, my invention comprises a blower whose impeller blades are confined between two opposed disks that are suitably spaced apart to contain said impeller blades whereby the air which enters centrally between the disks is directed with centrifugal action, radially from the impeller into the casing of the blower.

Also as an essential feature of my invention, the blower casing is provided, at one side thereof opposed to the outlet side, with a series of curved guides, the series having the general form of a stepped or sectional annulus, each guide, or section of the annulus, having curved characteristics which respectively, in conjunction with the surrounding wall of the blower serve to turn the air stream so as to change its course from a circular path in which it exerts radial force, into a circular, rearwardly directed path for delivery in a hollow whirling column.

Other features and advantages of my invention will hereinafter appear.

35 In the drawings:

Figure 1 is a side sectional view of a blower equipped with my improved impeller and fluid flow directing means.

Fig. 2 is a section on the line 2—2 of Fig. 1, looking toward the back of the fan casing, the arrow indicating the counter-clockwise rotation of the impeller blades.

Fig. 3 is a section on the line 3—3 of Fig. 2, and

Figs. 4, 5 and 6, taken respectively on the lines 4—4, 5—5 and 6—6 of Fig. 3 show different gradients represented in one of the like series of vanes constituting the air flow guiding annulus.

As has been promised, my invention re-

lates to means in conjunction with a blower for the delivery of fluid therefrom in a whirling column, without loss of pressure due to changing the direction of the fluid flow.

As an example of means for carrying out this invention I have illustrated herein a casing having the front plate 1, the rear wall 2, and the baffle 3 which is secured to studs 4 projecting inwardly from wall 2. Also there is shown the motor 5 whose shaft 6 engages the hub 7 of the fan or impeller. Said fan is here represented as composed of a rearward disk 8 and a forward disk 9, these disks being in parallel, spaced relation, and containing between them a series of curved impeller blades 10. While the forward disk 9 is of equal diameter with the rearward disk 8, said forward disk has a central opening, indicated at 11, for the entry of fluid which is admitted thereto as through the register 12. The hub 7, which constitutes the root portion of rearward disk 8, is convexed at 13 to guide the flow of fluid into the radial space between disks 8, 9.

Now it has been appreciated by me that the velocity of air or other fluid that is thrown with centrifugal force against the peripheral wall 14 of a blower casing, such as is here illustrated, is retarded in its subsequent passage over the baffle and toward the centrally disposed exit opening 15 in the rearward wall 2, so that the pressure that has been generated by the impeller is considerably lessened, with a consequent loss of efficiency in the delivered product. This is due to the fact that the acute angle required to be followed by the fluid stream in flowing between the baffle periphery and the peripheral wall 14 of the casing, exercises a braking effect upon its speed of travel.

Therefore my invention comprehends a means of easement for this retarding influence and consists of a curved guide that gradually translates the radial fluid flow force created by the impeller into a whirling force of flowing fluid with its axis directed at right angles to the plane of the radial force.

The curved guide referred to is in the form of an annulus composed of the steps or segments 16, disposed between the periph-

ery of the impeller and the inner surface of casing wall 14. Said segments therefore are contained within the circumferential space into which induced fluid is pressed by the 5 impeller blades. Each of the segments, which are identical in form, and may be described as of curved form, wedge shaped at both ends, has its entering edge 17 lying close to the forward wall 1 of the casing, whence it rises in 10 a gradual curve that is convex in cross-section, to its delivery point, where the segment has broadened out to lie close against the casing wall 14. The delivery edge 18 of each segment is adjacent the leading edge of a succeeding segment.

The segments may be said to have partially spiral surfaces between their leading and delivery edges that conduct the fluid flow in an easy turning movement to change its 20 radial direction into rearward direction, the change being effected so smoothly, without abruptness, that the initial velocity of the flowing fluid is in no way impaired.

As an example of one of the many uses to 25 which my improved blower may be applied, it is herein represented in association with a Todd rotary fuel oil burner, having the atomizer 19, air nozzle 20 into which air is delivered in a whirling column, Venturi cone 21, 30 and the other usual parts of this burner structure which need not be enumerated here since they form no part of my invention.

Variations within the spirit and scope of 35 my invention are equally comprehended by the foregoing disclosure.

I claim:

1. The combination with a blower having 40 a casing and an impeller therein, of a series of guide members disposed annularly within the casing, beyond the radius of the impeller, to turn the radially directed flowing fluid into a rearwardly directed whirling column, said guide members being partially spiral in form and wedge shaped at 45 both ends with their entering edges lying parallel with the forward wall of the casing, and their delivery edges lying parallel with the peripheral wall of the casing.

2. The combination with a blower having 50 a casing and an impeller therein, of a series of guide members disposed annularly within the casing, beyond the radius of the impeller, to turn the radially directed flowing fluid into a rearwardly directed whirling column, said guide members being partially spiral in form and wedge shaped at 55 both ends, with their entering edges lying against the forward wall of the casing, and their delivery edges lying against the peripheral wall of the casing.

3. The combination with a blower having 60 a casing and an impeller therein, of a series of guide members disposed annularly within the casing, beyond the radius of the impeller, to turn the radially directed flow-

ing fluid into a rearwardly directed whirling column, said guide members presenting surfaces that are convex in cross-section and being partially spiral in form and wedge shaped at both ends, with their entering edges lying parallel with the forward wall of the casing, and their delivery edges lying parallel with the peripheral wall of the casing.

4. The combination with a blower having 75 a casing and an impeller therein, of a series of guide members disposed annularly within the casing, beyond the radius of the impeller, to turn the radially directed flowing fluid into a rearwardly directed whirling column, said guide members presenting surfaces that are convex in cross-section and being partially spiral in form and wedge shaped at 80 both ends, with their entering edges lying against the forward wall of the casing, and their delivery edges lying against the peripheral wall of the casing.

New York, N. Y., September 23, 1930.

HARRY MEACHEM.
